BUILDING CONSTRUCTION

Earl E. Jones, Houston, Tex.; Mae Jones, executrix of said Earl E. Jones, deceased, assignor to J & B Steel Products, Inc., Houston, Tex., a corporation of Texas

Application January 28, 1950, Serial No. 141,128

7 Claims. (Cl. 189—86)

1

This invention relates in general to a modular building construction and has for its primary object the production of an improved building construction especially adapted to be fabricated from metal or the like and applicable also to the use of other materials such as concrete in combination with metal, and which will be cheap to manufacture, easy and quick to erect, and very sturdy once it has been erected. It is also an object that such construction permit easy dismantling and re-erection of the building in a different place or in different floor plans.

Many attempts have been made in the past to devise a construction which will make possible the efficient assembly of steel or concrete panels or the like upon framework which may also be of steel but in such attempts many difficulties have been encountered and failures have been experienced because of one or more factors such as the excessive expensive manufacture, the costly or ineffective methods employed for securing the metal or other panels to the metal framework, the skilled labor and special tools required in such assembly, the unattractiveness of the finished product, or the lack of strength and durability in the finished product.

It is, therefore, a more specific object of this invention to provide a building construction which will make possible the application of metal panels, or panels of other materials to a frame without the use of mortar, screws, bolts or nails or of any special tools or skill.

Another object is to provide a building construction which will make possible the application of non-nailable metal or other panels to a metal frame in such fashion that neither the panels nor the frame is altered to impair its future usefulness.

Another object is to provide a building construction which will make possible the application of metal or other non-nailable panels to a metal frame without the use of bolts, rivets, nails, or of any special tools or skill.

Another object is to provide a building construction embodying imperforate wall panels which may be readily assembled or disassembled without special tools and without any alteration or damage such as to impair suitability for reuse.

Another object is to provide a building construction embodying non-nailable imperforate wall panels without the use of mortar or the like.

Another object is to provide a building construction embodying imperforate metal or plastic wall panels without the use of adhesive.

2

Other objects and advantages of this invention will become apparent from the following description taken in connection with the accompanying drawings wherein like numerals represent corresponding parts throughout and wherein is illustrated by way of example a structure embodying two possible modifications of wall design made in accordance with this invention.

Referring now more in detail to the drawings: 10 Figure 1 is a modified perspective view illustrating a section of a wall constructed in accordance with this invention, showing principally the exterior view thereof.

Figure 2 is a horizontal cross section through 15 a corner of the wall structure illustrated in Figure 1 taken along the line 2—2 of Figure 1.

Figure 3 is a vertical cross section through the 20 wall structure illustrated in Figure 1, and through a fragment of roof and ceiling structure which may be employed therewith.

Figure 4 is a view similar to Figure 3 but through a wall at right angles to that shown in Figure 3.

Figure 5 is an enlarged fragmentary perspective, 25 with parts broken away and shown in cross section, illustrating one modification of this invention by which the metal face panels illustrated may be readily secured to a metal framework, this view being taken from the front side of the wall structure.

Figure 6 is a view similar to Figure 5 but taken 30 from the opposite side of the same joint structure, parts in this figure likewise being broken away and shown in cross section for purposes of illustration.

Figure 7 is a view similar to Figure 6 but illustrating the modification of ceiling structure shown in Figure 3 which may also be employed on the inner wall panels instead of that employed on the wall panels as shown in Figures 5 and 6.

Figure 8 is a fragmentary view similar to a portion of Figure 3 showing a vertical cross section through a portion of a cement panel structure embodying the securing means of this invention.

It is contemplated that the wall structure illustrated which is made in accordance with this invention, shall be mounted upon a foundation 50 consisting of a concrete slab or its equivalent, this slab being so constructed that if desired it may form a portion of the floor of the building construction. Of course, the body 1 may be formed to serve merely as a foundation and other floor structure provided.

Secured to this slab as a base for the frame-

work of the walls is a sheet metal support member 2 on which are carried upturned flanges 3 and 4 which, as will presently be shown, serve as keepers for the lower edges of the face panels of the inner and outer walls respectively. This support 2 may be secured to the slab 1 by any suitable means such as by the bolts 5.

The keeper flange 4 is provided by a part of the sheet 2 which extends down over the corner 6 of the slab 1 and is then turned up to provide the keeper flange 4. The keeper flange 3 is provided by a part which may be separate from and secured to the sheet 2 but which has an upstanding flange 7 that actually carries on its upper edge the offset keeper flange 3.

The wall structure is made up primarily of the substantially vertical and parallel T-beams or studs 8 and 9 which respectively form the inner and outer wall panel supports. Each of these supports has a front panel receiving surface on its cross flange as indicated by the numerals 10 and 11 respectively, all of the cross flanges which provide the panel receiving surfaces for the inner wall panels being in one plane and all the panel receiving surfaces of the supports for supporting the outer wall panels likewise being in one plane. It will be understood that the T-member supports or studs 8 and 9 may be of other cross section and construction so long as they provide front panel receiving surfaces and the latching surfaces hereinafter described. They may be cross braced and connected to each other in any desired fashion, such cross bracing and connections not being shown here in detail because they form no part of this invention and might tend to confuse the illustration shown in the drawing, but being exemplified by the cross members 12 and 13 adjacent the lower and upper ends of the studs respectively.

In addition to the fact that the front faces of the flanges 10 and 11 provide face panel receiving surfaces, the rear faces of these cross flanges provide rearwardly facing latching surfaces as will presently be described.

In front of the keeper provided by the upstanding flange 7 there is an upstanding flange 14 adapted to be engaged by the clips 15 on the snap-on base 16. The hollow interior of this base will, if desired, serve as a housing for electric wires, et cetera.

At the upper ends of the stud members 8 and 9 there may be provided a cross connecting sheet metal bearing plate 17 having a center section 18 fitting between the sheet metal plates 21 and 22. Truss spacing plate 17 has portions 19 and 20 which rest upon those portions of plates 21 and 22 that overlie the upper ends of the inner and outer stud sections 8 and 9 respectively. Spacing plate 17 is secured as by welding or other suitable means to the roof trusses. The plates 21 and 22 both have parts extending downwardly along the inner extremities of the legs of the studs and inturned flanges 23 and 24 at the lower edges of such parts, said flanges 23 and 24 resting on and secured to the cross braces 13.

Resting on top of the wall framing just described and preferably secured to the spacers 17 are the roof trusses which, in the form illustrated, are made up of the bottom chord members 25 which also serve as ceiling joists, and top chord members 26 which also serve as rafters. The bottom chords in the illustration are each formed of two angle bars 27 and 28 disposed back to back (see Fig. 4) and spaced apart to receive between them flat web tie members 29 and

30, to which the angle bars are welded or otherwise suitably secured. The top chords are similarly formed of two angle bars 31 and 32 disposed back to back and spaced apart to receive tie members. Adjacent the eave, the tie member 30 which is secured between the angles of the bottom chord extends upwardly between the angles of the top chord and is secured thereto to tie the chords together. It also extends above the angles of the top chord as at 33 and this extension is perforated for a purpose presently to be set forth. At a position directly opposite the tie member 29 there is provided another tie member 34 which extends between and is suitably secured to the angles of the top chord and is tied to the tie member 29 of the bottom chord by a short angle section 35 secured to both tie members 29 and 34. Tie member 34 also extends above the angles of the top chord at 36 and is perforated at 31 similarly to the tie member 30. The gable trusses (Fig. 4) may be modified somewhat by forming the top and bottom chords of single angles 38 and 39 joined together by T-section ties 40. Ties 40 should be aligned with the studs in the lower wall so as to form in effect extensions thereof if it is desired that the joints between the gable panels be aligned with those in the wall below. The angle forming the bottom chord 39 should be disposed with its vertical flange remote from the outer wall surface so that the cross flanges of the T-section ties 40 may extend as close as possible to the upper ends of the studs, but the angle forming the top chord 38 should have its vertical flange on the outside so that it may provide an abutment for the upper edges of the gable panels.

The roof construction comprises sheathing 41 which may be of wood or other suitable material, with sheet metal strips 42 laid on top. The sheet metal strips are provided with nesting inverted channels 43 and 44 at their adjacent edges interfitting with each other and fitting over the upper perforated ends of the tie members 30 and 34. Bolts or the like 45 are inserted through the perforated ends of the tie members and registering perforations in the inverted nested channels to hold the sheet metal strips in place. Gutters 46 may be provided with flanges 47 extending from the eave 48 a short distance upwardly between the sheathing and the roofing strips. A shield 49 may be provided behind the gutter for a purpose presently to be set forth.

Referring now more particularly to the construction and mounting of the inner wall face panels, it will be seen that these are illustrated as being made of sheet metal having flat outer surfaces forming the flush wall face. At the lower edge of the lowermost of these panels which bears the numeral 50, the sheet metal is turned inwardly as shown at 51 to provide a rearwardly offset flange 52 which is inclined downwardly and away from the face 50 of the panel and which has a front face providing a latching surface engaging with the rear surface of the keeper 3. This engagement, it will readily be perceived, is a wedging engagement which will hold the lower edge portion of this panel tightly in position with respect to the panel support members 8. In this connection it will also be seen by reference to Figure 2 that each of the face panels is made of such thickness that it will be said to have abutment parts 53 overlying and abutting a cushioning strip 54 of rubber or the like on the front panel receiving surface 10 of one of the panel supports 8 to provide for backing and

supporting of the face panels. It will also be seen by reference to Figures 3, 5 and 6 that the panel 50 has at its upper edge an inturned portion 55 which on its inner edge is formed in an upwardly facing flange 56, the front surface of this flange providing a latching surface which is inclined upwardly and slightly toward the front face 50 of the panel, and which is adapted to receive the keeper bar 57. This keeper bar 57 as will be seen extends in front of the flange 56 and engages the rearwardly facing latching surfaces on the rear surfaces of the cross flanges of the adjacent supports 8. Thus, these bars 57 serve as keepers for the latching surfaces provided by the front faces of the flanges 56.

The lower edge of each of the upper inner face panels 58 and 59 is provided with an inwardly extending portion 60 and with a down turned flange 61 which provides upon its front face a latching surface adapted to engage the rear face of the flange 56 just below. All of the panels except the lowermost are provided with arrangements on their lower edges and are provided on their respective upper edges with arrangements identical with that on the upper edge of the lower panel. A removable bar 57 is provided as a keeper for each of the adjacent upper and lower edges of such panels and for the upper edge of the top panel. It is to be noted that the bar 57 is preferably round in cross section. The flanges 56 and 61 are resilient and the interfitting parts are of such dimensions that they cannot be forced into full engagement with each other without slightly straining these resilient flanges, the resultant of this situation being that when the parts are forced into full engagement with each other the face panels will be held firmly against the panel receiving surfaces of the supports 8.

The structure of the outside wall is similar in all respects to that of the inside wall just described.

It is to be noted that when used as an outside wall the structure described is weatherproof because rain or the like cannot beat into the joint between the two inwardly extending parts 55 and 60 and reach the interior wall because of the upstanding flanges on the upper edges of the respective panels.

While it has been described that each of the wall panels illustrated is made of sheet metal, the inner faces of these sheet metal panels may be filled or covered with plastic or cement or lined with insulating material as illustrated if that be desired. It will be appreciated that the metal latching parts may be secured to cement or plastic panels in any desired manner, one such arrangement being shown in Figure 8 in which cement or plastic panels 62 have latching parts 63 and 64 anchored in their upper and lower edges respectively, such parts corresponding in shape and function to the latching parts 55 and 60 heretofore described. These parts 63 and 64 are shown anchored in the panels 62 by means of integral flanges 65 and 66 respectively, bedded in the material of the panels. The spaces between adjacent edges of such panels may be filled with mortar if desired, or caulked, as shown at 67.

While it is possible to use the same latching arrangement as just described for securing ceiling panels in place a more suitable though kindred arrangement for this purpose is illustrated in the upper portion of Figure 3. It is to be understood also that the arrangement shown

as securing ceiling panels in place in the upper portion of Figure 3 may, if desired, be employed for securing inner wall panels to their supports.

In the structure shown in the upper portion of Figure 3 ceiling panels 68 are illustrated, these panels being of a construction and similar to the wall panels heretofore described in that they have smooth, exposed faces and are of a width to span the distance between adjacent ceiling support members or joists 25 and have parts bearing against such members. However, it has been found expedient in ceiling panel structure to provide each of the panels 68 with inturned flanges 69 having channel shaped portions 70 open toward each other at the inner extremities of the flanges 69. Bridging the spaces between and extending into each of the channel shaped portions 70 is a keeper bar 71 crimped longitudinally into a shallow V-shaped cross section. The ends of this bar extend over the top surfaces of adjacent support flanges 72 and serve to suspend the panels 68 from the panel supports. The flanges of the channel shaped parts 70 which are most remote from the panels 68 are inclined toward each other and slightly away from the panels 68 at substantially the same degree as the inclination of the two legs of the V-shaped cross section of the bar 71. Thus it will be seen that when two adjacent panels are pushed toward each other with a bar 71 between the channel shaped sections 70 and the ends of such bar engaging the flanges 72, the panels 68 will be drawn into tight engagement with the panel support flanges 72.

The last panel 68 adjacent at a side wall is held by a keeper bar 73 which is similar to one-half the bar 71 but is integral with a pusher strip 74 by which it is intended to be pushed into the channel 70 of the last panel 68 to draw this last panel tightly against the supports 72 at the edge closest to the side wall of the building, and to compress the entire row of panels 68 together. It will be noted that alignment of panels may be accomplished by loosening one side and tightening the other.

The strip 74 extends down along the edge of panel 68 to a point adjacent the lower face of panel 68 where it is formed with a fold 75 extending first away from then folded back toward panel 68. Bolts 76 are welded or otherwise secured to strip 74 and have threaded portions extending freely through openings in strip 21. A nut is threaded onto each bolt 76 between strips 74 and 21 and it will be seen that turning the nut toward strip 21 will force keeper bar 73 into tight engagement with its channel 70.

A molding 77 may be provided for bridging the space between the topmost inside wall panel 59 and the next adjacent ceiling panel 68, such molding being secured in place by any suitable means such as by an integral flange 78 which extends into and is frictionally held by fold 75.

From the foregoing it will be seen that in erecting a building of the character described, the framework, including the studs or supports 8 and 9, will be first erected with windows and doors in place and the whole secured together. The roof trusses will next be put in place with the part 17 serving to position roof trusses with respect to the wall frames.

Next, the outside wall panels will be put in place beginning at the bottom. Then the gutter may be added and the roofing strips put on and secured in place.

Next, the inside wall panels are put in place in

the same fashion beginning at the bottom and the bar holding the uppermost edge of the top panel of the inside wall can be put in place from inside the building.

Next, the ceiling panels will be put in place beginning at the wall which is not shown but which would be over to the right of the structure shown in Figure 3 and working toward the left. The last panel 63 that is to be put in place is held upwardly in place by hand or other suitable means while the keeper 73 is moved to engage channel 70, whereupon a wrench is inserted between the adjacent ceiling and inner wall panels and engaged with the nut on each bolt 76 for the purpose previously described. It will be understood that the keeper tightening arrangement may be employed at both extremities of the ceiling and that by loosening one and tightening the other an entire row of ceiling panels may be shifted to align them with adjacent rows.

Last of all, the molding 77 may be put in place and secured by pressing flange 78 into fold 75.

At any time desired after the lowermost wall panel has been put in place, the baseboard 16 may be mounted.

Partitions may be of construction similar to those described for outside walls or ceiling.

The outside corner of a building constructed in accordance with this invention is preferably covered with long, angle shaped panels and may be secured in place by a latching structure such as hereinbefore described or by any other suitable means which may be desired.

It will further be appreciated that each of the latching parts and the cooperating elements not only of the inner wall panels and their keepers, but also of the outer wall and ceiling panels and their keepers as well, are preferably made of resilient material and are made of such relative sizes that they cannot be forced into full engagement with each other without some straining of the material of which they are constructed, so that once they are forced into full engagement with each other these panels will be held firmly against their respective panel supports.

Thus there has been disclosed a structure in which all of the objects and advantages sought by this invention will be attained although it will be apparent that departures from the exact arrangements and configurations of parts may be made without departing from the spirit and scope of this invention, the spirit and scope of the invention being limited only by the prior art and by the terms of the appended claims.

The invention having been described, what is claimed is:

1. A building construction comprising a frame having a plurality of spaced parallel panel supports with flat panel receiving faces presented outwardly and a keeper between each pair of supports near one end thereof, a plurality of face panels each bridging the space between and overlying a part of the panel receiving face of each of said pair of supports and having an edge juxtaposed to an edge of another of said panels, one of such panels having a latching part projecting between said supports at one edge and engaging behind a part of said keeper and holding said one edge of the panel against the frame, and the adjacent edges of juxtaposed panels having complementary parts projecting between said supports and toward each other and forming together a partially closed channel extending between said supports, and a removable bar member lying in said channel and projecting behind a part of each

of said supports and providing a keeper holding the adjacent edges of said panels in place against said supports.

2. A building wall construction comprising a pair of spaced substantially upright supports having front panel receiving faces and rearwardly facing latching surfaces, keepers fixed with respect to said supports adjacent the lower end thereof, a series of face panels bridging the space between said supports and engaging said panel receiving faces and being disposed one above the other in juxtaposed relation to each other, each of said panels having thereon adjacent its lower edge a rearwardly offset, downwardly extending latching part, such part on the lowermost panel being in latching engagement with the said fixed keeper, each of said panels having adjacent its upper edge a rearwardly offset, upwardly extending and upwardly open keeper engaging latching part, a removable keeper in each such keeper engaging latching part and extending therefrom into engagement with said latching surfaces on the supports, and the downwardly extending latching part on each of said panels above the lowest panel engaging down behind a keeper part on the next lower panel.

3. A building construction comprising a plurality of laterally spaced panel supports having front panel receiving surfaces and rearwardly facing latching surfaces, a plurality of face panels each having rearwardly facing abutment parts along two opposite edges in abutting relation to said panel receiving surfaces and having latching parts on its other two opposite edges offset rearwardly beyond the planes of the adjacent rearwardly facing latching surfaces, said latching parts on each panel extending generally parallel to but inclined slightly with respect to the latching surfaces on the supports, each of said panels having one of its edges with latching parts juxtaposed with one of the edges with latching parts on another of said panels, and a removable bar for each pair of juxtaposed edges of adjacent panels engaging and lying between the adjacent latching parts on said pair of panels on the one hand, and said latching surfaces on the adjacent supports on the other hand and serving as a keeper for the adjacent latching parts of both the juxtaposed panels.

4. A building construction comprising a plurality of laterally spaced panel supports having front panel receiving surfaces and rearwardly facing latching surfaces, a plurality of face panels each having rearwardly facing abutment parts along two opposite edges in abutting relation to said panel receiving surfaces and having latching parts on its other two opposite edges offset rearwardly beyond the planes of the adjacent rearwardly facing latching surfaces, said latching parts on each panel extending generally parallel to but inclined slightly with respect to the latching surfaces on the supports, each of said panels having one of its edges with latching parts juxtaposed with one of the edges with latching parts on another of said panels and a removable bar for each pair of juxtaposed edges of adjacent panels engaging and lying between the adjacent latching parts on said two panels on the one hand, and said latching surfaces on the adjacent supports on the other hand and serving as a keeper for the adjacent latching parts of both adjacent panels, said latching parts being of resilient material and the various elements which cooperate to perform the latching

function being of relative sizes requiring distortion of the latching parts when the said elements are forced into full latching engagement with each other.

5. A building construction comprising a plurality of laterally spaced panel supports having front panel receiving surfaces and rearwardly facing latching surfaces, a plurality of face panels each having rearwardly facing abutment parts along two opposite edges in abutting relation to said panel receiving surfaces and having latching parts on its other two opposite edges offset rearwardly beyond the planes of the adjacent rearwardly facing latching surfaces, said latching parts on each panel extending generally parallel to the latching surfaces on the supports, each of said panels having one of its edges with latching parts juxtaposed with one of the edges with latching parts on another of said panels, and a removable bar for each pair of juxtaposed edges of adjacent panels engaging and lying between the adjacent latching parts on said two panels on the one hand, and the said latching surfaces on the adjacent supports on the other hand and serving as a keeper for the adjacent latching parts of both adjacent panels.

6. A building construction comprising a plurality of laterally spaced panel supports having front panel receiving surfaces and rearwardly facing latching surfaces, a fixed keeper between said supports and adjacent the lower extremities of such surfaces, a plurality of juxtaposed face panels each having rearwardly facing abutment parts along two opposite edges in abutting relation to said panel receiving surfaces and having latching parts on its other two opposite edges offset rearwardly beyond the planes of the adjacent rearwardly facing latching surfaces, said latching parts on each panel extending generally parallel to the latching surfaces on the supports, the latching parts on the lower edge of the lowermost panel being in latching engagement with the keeper fixed between said supports, and a removable bar for each pair of juxtaposed edges of adjacent panels engaging and lying between the

adjacent latching parts on said pair of panels on the one hand, and said latching surfaces on the adjacent supports on the other hand and serving as a keeper for the adjacent latching parts of both adjacent panels.

7. A building construction comprising a plurality of laterally spaced panel supports having front panel receiving surfaces and rearwardly facing latching surfaces, a lower fixed keeper extending between said panel supports adjacent the lower ends thereof, a plurality of juxtaposed face panels each having rearwardly facing abutment parts along two opposite edges in abutting relation to said panel receiving surfaces and having latching parts on its other two opposite edges offset rearwardly beyond the planes of the adjacent rearwardly facing latching surfaces, the latching part on the free edge of one of the lowermost panels being in engagement with the said fixed keeper surface which is disposed rearwardly of the panel receiving surfaces, the latching parts on each panel extending generally parallel to the latching surfaces on the supports, and a removable bar for each pair of juxtaposed edges of adjacent panels and for the free edge of the other end panel engaging and lying between the adjacent latching parts on each two adjacent panels and the free edge of the other end panel on the one hand, and said latching surfaces on the adjacent supports on the other hand and serving as a keeper for the adjacent latching parts of both adjacent panels and the free edge of the other end panel.
